(57) **CLAIM**

The ornamental design for an eyeglasses frame with front-folding crossing temples or similar article, as shown and described.

DESCRIPTION

This application is related to concurrently filed U.S. patent application Ser. No. 09/943,064 entitled “Eyeglasses Frame with Rotatable Temples,” and is related to concurrently filed U.S. Design patent application Ser. No. 29/147,529 entitled “Eyeglasses Frame with Front-Folding Overlapping Temples,” and is related to concurrently filed U.S. Design patent application Ser. No. 29/147,528 entitled “Eyeglasses Frame with Front-Folding Parallel Temples”.

FIG. 1 is a front view of an eyeglasses frame with front-folding crossing temples;

FIG. 2 is a top view thereof; and,

FIG. 3 is a perspective view thereof.

The portion of the article depicted in broken lines is for illustrative purposes only and forms no part of the claimed design.
